ENGINE STARTING MECHANISM

Romeo M. Nardone, Westwood, N. J., assignor to
 Bendix Aviation Corporation, Bendix, N. J., a
 corporation of Delaware

Application February 8, 1943, Serial No. 475,159

2 Claims. (Cl. 123—179)

This invention relates to starting mechanism for internal combustion engines and more particularly to engine starters of the inertia type.

An object of the present invention is to provide an inertia starter of the concentric type embodying novel actuating means operable at a point in the rear of and at a distance from the starter. For example, when the starter is applied to an aeroplane engine, said means are adapted to be actuated from the cockpit of the aeroplane.

Another object is to provide novel means for operatively connecting the starter to the engine, whereby the energy stored in the flywheel of the starter is rendered effective to start the engine; 15 said "meshing" means being so constituted as to be more readily adjustable than is the meshing mechanism of prior devices of similar character.

These and other objects of the invention will become apparent from inspection of the following specification when read with reference to the accompanying drawings wherein is illustrated the preferred embodiment of the invention. It is to be expressly understood, however, that the drawings are for the purpose of illustration only, and are not designed as a definition of the limits of the invention, reference being had to the appended claims for this purpose.

In the drawings:

Fig. 1 is a longitudinal sectional view of a device embodying the invention;

Figs. 2 and 3 are end views from opposite ends;

Fig. 4 is a transverse sectional view of the motor brush assembly;

Fig. 5 is a transverse sectional view of the motor terminal box;

Fig. 6 is a fragmentary sectional view showing the adjustable control elements of the meshing means;

Fig. 7 is a fragmentary sectional view showing another part of the meshing control; and

Fig. 8 is a fragmentary sectional view showing clutch assembly on the motor shaft.

Referring to Figs. 1 and 2, the starter mechanism comprises a housing including a flanged inner portion 4 adapted to be attached to the engine casing (not shown). Similarly attached to the outer flange of member 4 is a housing member 6, having an annular face to receive the annular end section 187 of the flywheel-energizing motor. The section 187, in turn, has an annular face to receive the main section 7 of the motor, and also has a cylindrical bearing section 55

8 to receive a manually rotatable shaft 9 disposed in parallelism with motor housing 7.

Shaft 9 carries, on the end thereof that projects outwardly from housing 8, a sleeve 11 adapted to be engaged by a hand-crank (not shown) of a type that is operable from the cockpit of the plane on which the starter is installed. Shaft 9 is shown as terminating in a gear 13 which meshes with a gear 14 that is keyed to the hub extension shaft 15 of a barrel 24 which is rotatably mounted in the flanged housing member 4. The closed end of barrel 24 is provided with pockets which receive sleeves 29, one of which is shown in section in Fig. 1. Each of these sleeves, which are spaced at intervals of 120° around the barrel 24, is secured to a retaining ring 31. Screws 32 pass through the sleeves and are threaded into the barrel 24. Ball bearings 33 are mounted on these sleeves and rotatably support three planetary gears 34, one of which is shown in section, and one in elevation.

Integral with the flanged housing member 4 is a double annular gear 36 which surrounds and meshes with the twin sets of planetary gears 34. 25 Each of the latter's gears is in mesh with a sun gear 38, both of which are rotatably mounted on the hollow shaft 15, and one of said sun gears is formed integral with the hub of a spur gear 39 which is likewise rotatably mounted about the shaft 23, concentric therewith.

In engagement with spur gear 39 is a pinion 41 that is formed integral with the inner end of a shaft 42. The housing member 4 is provided with a hub 43 concentric with the longitudinal axis of shaft 42, and positioned in said hub are ball bearings 44 which rotatably support the hub of a flywheel 46, said hub being keyed to the shaft 42.

The energy of the rotating flywheel 46 is imparted to the usual starter jaw (engine-engaging member) 40 adapted to mesh with, but normally out of engagement with, a similar jaw (not shown) formed on the end portion of the crank-shaft of the engine to be started, or an extension thereof. A yieldable clutch is interposed between the starter jaw 40 and barrel 24, which latter, during the starting operation, is driven by the flywheel through the train of gearing described above. In the form shown the clutch mechanism comprises a plurality of plates 139 in interleaving and frictional engagement one with the other. One half of said plates are splined to the inner surface of the surrounding barrel 24, closely adjacent the closed end of the latter. Alternating with the discs that are splined to the barrel, are

the remaining half of the discs which have splined engagement at their inner peripheries with the outer surface of a nut 138. A plurality of coiled springs 143 have operative engagement at their outer ends with a clutch adjusting nut 154 threaded onto the outer end of barrel 24. Preferably springs 143 are maintained in spaced relation by means of suitable posts 155 which project inwardly from a disc 153, contacting with the inner face of said nut 154. Threaded within nut 138, and adapted for rotary movement therewith and longitudinal movement relative thereto, is a shaft 156 provided with splines at its outer end to receive the interiorly splined tubular portion of starter jaw 40.

The motor housing 7 is shown as a sectional housing, and on examination of Figs. 2 and 3 it will be seen that on the outer section there is mounted a lateral extension 171 (shown also in Fig. 5) including a threaded boss 172 to which attaches a flexible shielding conduit (not shown) through which extend the electrical connections for attachment to the terminal posts 173 and 174 (see Fig. 5), both of which are mounted in a suitable block 175 of insulating material. The larger terminal post 173 is in turn electrically connected (by way of the series field and clamp 170, Fig. 4) to the commutator brushes of the motor, the said brushes being indicated at 176, 177, 178 and 179 in Fig. 4. The smaller terminal post 174 receives a conductor 181 leading (by way of supporting block 181a, Fig. 4) to the terminal post 182 (see Fig. 7) which supplies current to the winding 183 constituting part of the solenoid assembly which operates the meshing mechanism by which the engine engaging element 40 is controlled in its engaging and disengaging movements. As shown in Figs. 1, 2, 3, 6 and 7, this meshing mechanism includes a rod 191 having a reduced portion 192 extending through the screw shaft 156 and the engine engaging element 40 and held to the latter by a nut 193 threaded to the end of the rod; the shoulder formed by the junction of the portions 191 and 192 being in abutment with the screw shaft 156. The meshing mechanism further includes a coiled compression spring 196 interposed between the screw shaft 156 and the element 40 and surrounding the rod 192, also a yoke or bifurcated lever 197 (see Fig. 6) pivotally connected to the end of rod 191, as indicated at 198, and adapted to swing about a rock shaft 199 (Figs. 2 and 6) in response to energization of the winding 183 of the solenoid assembly; such energization being effective to swing the lever 197 by reason of the intervening connections which include the movable pole piece 201 of the solenoid assembly, the plunger 202, the lever 203, one end of which is pivotally connected to the end of plunger 202, as shown best in Fig. 2, and the rock shaft 199 which is keyed to the central hub of the lever 203 and therefore rotates in an amount corresponding to the swinging of the said lever. This rotation of the rock shaft 199 is communicated to the lever 197 by way of a connecting lever 205 whose end has engagement with the lever 197, as indicated in Fig. 6, and therefore causes the said lever 197 to swing in a clockwise direction as viewed in Fig. 6 in response to clockwise rotation of the shaft 199 to which the lever 205 is keyed. Such movement of lever 197 causes the rod 191 to move to the left and thereby move the engine engaging element 40 into engine engaging position; the movement being yieldably opposed and adjustably controlled by means operating upon the opposite extension

211 of the lever 197. As shown in Fig. 6 this control means includes a plunger 212 slidable in a cylindrical opening formed in the housing section 6 and threaded in its outer portion to receive an adjusting and retaining nut 213. The control mechanism further includes a coiled compression spring 214 mounted in the aligned recesses of the members 212 and 213 and therefore yieldably urging the lever 197 in a counter-clockwise direction at all times. Due to the fact that the lever 197 is freely rotatable about the rock shaft 199 and conversely that the rock shaft 199 is rotatable in a counter-clockwise direction as viewed in Fig. 6 without producing any corresponding movement of the lever 197 (since the intermediate lever 205 communicates motion to the lever 197 only in a clockwise direction), it is possible for the lever 203 and the rock shaft 199 to be actuated in the counter-clockwise direction without producing any shifting of the lever 197 or the rod 191 and hence without producing any disengaging thrust upon the engine engaging element 40. Therefore, the element 40 may remain in the engaged position under the continuing influence of the cranking effort being applied thereto by way of the inter-engaged screw elements 138 and 156 so long as the energy previously stored in the flywheel 46 remains unexhausted—the only opposing force during this cranking action being the externally adjustable spring 214. Therefore, premature disengagement of the engine engaging element 40—as for example by a premature shifting of the lever 203 in a direction causing the intermediate lever 205 to move away from the lever 197—is effectively prevented.

A unidirectional clutch is shown in Figs. 1 and 8 as being interposed between the splined end portion 251 of the motor armature shaft 252 on the one hand, and the inner surface 255 of the flywheel 46 on the other. As shown this clutch includes an inner race 256, an outer race 257, and a plurality of rollers 258 operating as a one-way motor to the flywheel substantially as in my Patent No. 2,068,462, granted January 19, 1937. The use of this clutch facilitates manual operation of the starter through the means connecting to the manually operable shaft 11 as energization in this manner can be brought about independently of any rotation of the armature assembly 252 and thus the frictional resistance of the brushes 176 to 179, inclusive, is avoided.

When the starting system includes an auxiliary ignition coil (as in Lansing Patent No. 2,195,151, granted March 26, 1940) the latter (not shown here) may be energized by connecting it in series with solenoid winding 183. This may be done by attaching a wire to terminal post 185 (Fig. 7) and leading it out through the opening that is shown in Fig. 7 as closed by removable plug 186. The plug is provided to close this opening in those installations which do not include such an auxiliary ignition coil; and in such installations the post 185 is connected directly to ground, as by attachment of a grounding strip, extending from the post 185 to the end section 187 of the motor housing 7.

An important feature of the "meshing" mechanism is the manner in which energizing current is supplied to the solenoid winding 183, namely, by running the wire 181 longitudinally through the motor, internally of the housing, to connect terminal 174 with solenoid terminal 182. The wire is conveniently passed through the space between adjacent field windings, and then

through a hole (not shown) in the end section 187 of the motor housing 7. This method of delivering current to the solenoid eliminates the need of separate external connections and thereby simplifies the electrostatic shielding problem, as the single conduit terminal 172 serves for both motor and solenoid energization.

What is claimed is:

1. In combination with an engine-engaging member, means for moving said engine-engaging member to engine-engaging position, said means including a shiftable rod and a linkage for shifting said rod, a housing enclosing said linkage, rod and engine-engaging member, resilient means yieldably opposing movement of said linkage in one direction, and means mounted on said

housing and adjustable externally of said housing for controlling the degree of opposition exerted by said resilient means.

2. In combination with an engine-engaging member, means for moving said engine-engaging member to engine-engaging position, said means including a shiftable rod and a linkage for shifting said rod, a housing enclosing said rod and engine-engaging member, resilient means yieldably opposing movement of said linkage in one direction, and means mounted on said housing and adjustable externally of said housing for controlling the degree of opposition exerted by said resilient means.
